TABLE LIGHTER

Katsuhiko Umeda, Tokyo, Japan, assignor to Westminster
Industries Inc., New York, N.Y.

Filed Dec. 29, 1972, Ser. No. 319,916

Term of patent 14 years

Int. Cl. D27—05

U.S. Cl. D27—39

FIG. 1 is an exploded view of a table lighter showing my new design;

FIG. 2 is a side elevational view thereof on a reduced scale;

FIG. 3 is a top plan view thereof on a reduced scale;

FIG. 4 is a bottom plan view on a reduced scale.

I claim:

The ornamental design for a table lighter, as shown and described.
